SKATE

John Chochkoff, Chicago, Ill.

Application March 17, 1934, Serial No. 716,022

1 Claim. (Cl. 208—183)

This invention relates generally to improvements in skates and has particular reference to an auxiliary retaining device or attachment for the skate supporting strap commonly called the ankle strap which is attached to the heel-plate of the skate.

The invention is adaptable to roller skates or ice skates.

Many of the skates now made by various manufacturers and in common use are provided with an adjustable ankle strap which is connected with or attached to the heel-plate of the skate and adapted to be passed around the ankle of the foot of the skater to thus support the rear end of the skates. Almost invariably where skaters use low shoes, such as oxfords or slippers, these heel-plate straps tend to and actually do slip to such position on the ankle of the skater just above the foot-wear that the portion of such strap contacting the ankle, when pressure is exerted upon its tightening, causes a rubbing of the strap on the exposed part of the ankle or foot and thus causes discomfort to the skater and many times injurious and painful sores on the feet of the skater.

One of the objects of my invention is to provide an attachment for skates which will retain the ankle or heel-plate strap in position on the foot-wear of the skater and prevent its movement up onto the foot portion above the low shoe.

Another object of my invention is to provide adjustable means connecting the ankle strap with the forward or front end of the skate.

Another feature of my invention is found in the provision of means connecting the ankle strap with the front end of the skate so constructed that such means will tend to follow the contour of the top of the foot-wear to lie close thereto.

Still another object of the invention is found in the provision of such ankle strap retaining means with a cap which is attachable at the front end of the skate and which cap protects the toe portion of the foot-wear.

A further object of my invention resides in the provision of an ankle strap retainer which consists of flexible adjustable means hingedly connected to a cap-like body which embraces the toe portion of the shoe and which is provided with an extension disposed underneath the sole-plate of the skate.

With the above and other objects in view, my invention consists in the novel combination, construction and arrangement of the various parts and members shown in preferred embodiment in the attached drawing, described in the following

specifications and particularly pointed out in the appended claim.

In the drawing:

Fig. 1 is a side elevation of a roller skate with part thereof in section, and embodying my invention.

Fig. 2 is a cross-section taken on line 2—2 of Fig. 1 and showing the connection of my invention to the adjustable clamps.

Fig. 3 is a perspective view of the toe-cap portion of my invention and an arcuate connecting link therefor.

Referring to the drawing, and particularly to Figs. 1, 2, and 3, my invention is shown as applied to a roller skate 10 which includes a sole-plate 11 and heel-plate 12.

It will be noted that the heel-plate 12 is perforated as at 12^A for the ankle strap 13 which extends around the outside of the heel-plate up-standing portion and is provided with a buckle 13^A 20 for adjustment to the foot.

The dotted lines in Fig. 1 show the ankle strap in the position it usually assumes and the full lines show the position of the ankle strap retained in contact with the shoe by my invention. 25

My improved ankle strap retainer, as shown in Figs. 1 to 3, inclusive consists of a strap-loop 14 which is preferably slidably mounted on the ankle strap 13 and which loop 14 carries a buckle 15.

To this buckle 15, I adjustably connect a strap 30 16 which is arranged to be secured to the forward or front end of the skate 10.

Various means for connecting the strap 16 to the front end of the skate may be employed, as for instance, one end of the strap 16 might be 35 riveted directly to the front end of the sole-plate 11, but I prefer to provide a metallic-toe-cap 17 which is formed to conform to the general form of a shoe toe so as to fit over the shoe toe portion and which toe-cap 17 is formed with a horizontal extension 17^A and provided with a centrally disposed elongated perforation 17^B.

The skate as shown in Figs. 1 and 2 is provided with a pair of sole retaining clamps 18 which are simultaneously movable in opposite direction by 45 means of their threaded engagement with the screw 19 which is rotatably mounted in the vertical rib 20 disposed beneath and from the sole-plate 11. The clamps 18 are slidably mounted on rivets 21 fixed to the sole-plate 11, and when 50 the clamps 18 are moved to their extreme outward positions they and their operating screw 19 may be removed from the skate to permit the insertion of the toe-cap 17 into place on the front end of the skate with the extension 17^A lying 55

underneath the sole-plate 11 and the rib 20 projecting through the slotted opening 17^B. The toe-cap being in place, the clamps 18 and screw 19 may then be reset into position on the skate.

5 The toe-cap 17 is preferably provided with a loop 17^C disposed centrally and integrally with the top portion thereof.

Obviously, the retaining strap 16 could be riveted directly to the loop 17^C but I prefer to insert 10 an arcuate metallic link 22 between one end of the strap 16 and the loop 17^C. The link 22 is provided with slots 22^A at its ends, one for the connection of the strap 16 thereto and the other for the connection of the loop 17^C thereto.

15 The purpose of my employment of this arcuate link 22 is to insure the retention of such ankle strap retaining means close to the top of the shoe, as clearly shown in Fig. 1.

I claim:

20 In a roller skate having a heel strap, vertical perforated rib disposed below the sole plate, a rotatable member mounted in the perforation of said rib and having oppositely formed screw

threads on the ends thereof, and a pair of sole-retaining clamps oppositely movable into adjusted positions by the threaded ends of said rotatable member, the combination with said heel strap of a removably mounted retainer adapted to retain the upper or forward portion of said heel strap below the shoe top, said retainer comprising a metallic toe cap having a concave portion adapted to receive the toe end of the shoe and an integral lateral portion having a perforation therein, said lateral toe cap portion being adapted to be inserted under the sole plate above said rotatable member so that said rib extends through the perforation in said lateral toe cap portion, the concave cap portion having an integral hook disposed above the shoe toe, an arcuate metallic link having transverse slots at its ends, one of said slots being insertable over said toe cap hook for connection thereto, and flexible adjustable means extending from said heel strap and through the other of said slots in said link.

JOHN CHOCHKOFF.
